US0D1104146S

(12) **United States Design Patent** (10) **Patent No.:** **US D1,104,146 S**
(45) **Date of Patent:** **** Dec. 2, 2025**

(54) **WRITING TABLET**

(71) Applicant: **Shenzhen Zhiheng Supply Chain Co., Ltd.**, Shenzhen (CN)

(72) Inventor: **Zhitian Li**, Guangdong (CN)

(73) Assignee: **Shenzhen Zhiheng Supply Chain Co., Ltd.**, Shenzhen (CN)

(**) Term: **15 Years**

(21) Appl. No.: **29/924,758**

(22) Filed: **Jan. 20, 2024**

(30) **Foreign Application Priority Data**

Oct. 16, 2023 (CN) 202330667130.0

(51) **LOC (15) Cl.** **19-06**

(52) **U.S. Cl.**

USPC **D19/113**

(58) **Field of Classification Search**

USPC D21/329, 468, 469, 470; D14/305, 315, D14/322, 328, 334-347, 403, 440, 250; D19/1, 5, 37, 59, 60, 75, 79, 83, 93, 99, D19/103, 110-114; D20/27, 28

(57) **CLAIM**

The ornamental design for a writing tablet, as shown and described.

DESCRIPTION

FIG. 1 is a first perspective view of a writing tablet showing my new design;

FIG. 2 is a second perspective view thereof;

FIG. 3 is a front view of FIG. 1;

FIG. 4 is a rear view of FIG. 1;

FIG. 5 is a left side view of FIG. 1;

FIG. 6 is a right side view of FIG. 1;

FIG. 7 is a top plan view of FIG. 1;

FIG. 8 is a bottom plan view of FIG. 1;

FIG. 9 is an enlarged view of the portion labeled 9 in FIG.

2; and,

FIG. 10 is an enlarged view of the portion labeled 10 in FIG.

1.

The broken lines in the drawings depict portions of the writing tablet that form no part of the claimed design.

1 Claim, 10 Drawing Sheets
